his Attorney

UNITED STATES PATENT OFFICE.

CECIL A. HEAD, OF ROYAL OAK, MICHIGAN.

ELECTRIC RADIATOR.

Application filed June 26, 1922. Serial No. 570,797.

To all whom it may concern:

Be it known that I, CECIL A. HEAD, a subject of the King of England, and a resident of Royal Oak, in the county of Oakland 5 and State of Michigan, have invented a new and useful Electric Radiator, of which the following is a specification.

My invention relates to electric radiators and has as its principal object improvements 10 in a structure set forth in my co-pending application for electric radiators, filed February 25, 1922, Serial No. 539204.

The invention further provides an electric radiator wherein the house wiring system 15 will not be subjected to a heavy load upon starting of the heating element.

Another important object of my invention is to provide an electric radiator wherein the water supply will be totally evaporated 20 and leaving the electrodes clean when not in use.

Still another object of the invention is to provide means for trapping all foreign matter such as rust, mud, etc., thereby insuring 25 operation of the device at all times and preventing corrosion of the electrodes.

With the preceding and other objects and advantages in mind, the invention consists in the novel combination of elements, construction and arrangement of parts and operations to be hereinafter enlarged upon, claimed and illustrated in the accompanying drawing, wherein:

Figure 1 is a view of my improved electric 30 radiator having parts shown in elevation and parts in vertical cross section; and,

Fig. 2 is a plan view of the electric heating element.

Referring in detail to the drawings where- 40 in like characters of reference designate like parts throughout the several views, the numeral 5 designates a steam generating chamber with which L shaped radiating tubes 6 communicate at diametrically opposite points 45 and at the upper end thereof. Extending laterally from the opposite end of the chamber 5 and at diametrically opposite points are head tube sections 7 which have communication with the tube 6 by way of T 50 couplings 8 the latter raising supporting legs 9 having base elements or feet 10. Detachably secured to the lower end of the generating chamber 5 is a cup or receptacle 11 formed with nonconducting material hav-

ing an annular flange 12 which is secured to the generator chamber 5 by bolts 13, the flange 12 and generator chamber 5 being spaced by a nonconducting ring 14. Arranged in the cup or receptacle 11 is a substantially cone shaped electrode 15 disposed centrally within the cup or receptacle 11 suspended from the side walls thereof. A binding post 16 extends through the bottom of the receptacle or cup 11 and is engaged with the electrodes 15, the binding post 16 being electrically connected with one terminal 17 of an electricity conductor 18 which is adapted to be arranged in the house or secured with any other desirable source of electrical energy. Encircling the electrode 15 and positioned against the side walls of the cup or receptacle 11, is an annular electrode 19 which is engaged by a binding post 20 passing through the cup or receptacle 11 and is connected with the other terminal 21 of the conductor 18. In order to obviate a continuous body of water from forming in the bottom of the receptacle or cup 11 due to the condensation of the steam, the bottom of the cup or receptacle 11 is formed with circumferential teeth or gutters 22 at a point between the electrodes 15 and 19. As the steam condenses, the latter passes down the sides of the electrode 15 and enters the gutters or spaces between the teeth 22.

Communicating with the tubes 7 is a water glass 23 having a drain 24 and leading from the drain 24 is a valve controlled pipe 25 which leads into the cup or receptacle 11 and has its outlet disposed over the highest point of the electrode 15. The water glass 23 is provided with a filling opening 26 into which the water is poured to fill the receptacle or cup 11.

In the operation of my invention of an improved heater, it will be obvious that as the water passes from the water glass 23 by way of the pipe 25 and flows into the spaced point of electrodes 15 and 20 the electric circuit will evaporate the water. As the water is evaporated it is circulated through the generator chamber and tubes. As condensation is formed, it passes into the gutters over the teeth 22 and completes a circuit through the electrodes to evaporate these small bodies of water. With this type of heating element, it will be seen that the starting of the operation of the same

will be gradual and will not subject the line 25 to a great load and the consequent blowing of the fuse elements in the circuit.

It is to be understood that the form of 5 my invention, herein shown and described, is to be taken as a preferred example of the same, and that various changes in the shape, size and arrangement of parts may be resorted to without departing from the 10 spirit of the invention or the scope of the subjoined claims.

Having thus described my invention, what 15 I claim as new and desire to secure and protect by Letters Patent of the United States, is:

1. An electric heater comprising a non-conducting receptacle, a centrally arranged electrode mounted therein, an annular electrode also mounted in the receptacle and 20 spaced from the central electrode, and two electrodes being adapted to be electrically connected by a body of liquid contained in the receptacle, the receptacle being provided with spaced gutters between the elec-

trodes to provide a continuous cup of water 25 in the receptacle after the main body of water has been evaporated.

2. An electric radiator comprising a generating chamber, radiating tubes communicating with the generating chamber, supporting legs engaged with the lower ends of the radiating tube, a water glass communicating with one of the radiator tubes and having a full opening and a tube leading from the water glass into the generator 30 chamber and a heating element arranged at the lower end of the generator chamber.

3. A combination with a radiator, of a heating element including a liquid receiving cup communicating with the radiator, 40 a central substantially conical electrode arranged in the cup, an annular electrode encircling the conical electrode and both being adapted to be electrically connected by a body of water contained in the receptacle, 45 the bottom of the receptacle being provided with gutters to receive condensation.

CECIL A. HEAD.
